W. C. MILLS

EXERCISING DEVICE

Filed Sept. 22, 1926

UNITED STATES PATENT OFFICE.

WALTER CECIL MILLS, OF WABASH, INDIANA.

EXERCISING DEVICE.

Application filed September 22, 1926. Serial No. 136,993.

The present invention relates to a combined exercising and amusement device, the primary object of the invention being to provide a device of this character including radiating arms to act as supports for persons hanging thereon, the arms being constructed so that they may revolve on a supporting post.

- An object of the invention is to provide 10 a device of this character whereby a person may support his weight by his arms while the device is being rotated, thereby strengthening the hands, wrists and arms of the person using the device.
- 15 A still further object of the invention is to provide an adjustable support whereby the device may be adjusted for use by tall or short persons.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

Referring to the drawing:

- 30 Figure 1 is a perspective view illustrating a device constructed in accordance with the invention, and illustrating how the device is used.

Figure 2 is an enlarged vertical sectional 35 view through the device.

Figure 3 is a sectional view taken on line 3—3 of Figure 2.

Figure 4 is a sectional view through the outer end of one of the supporting arms.

- 40 Referring to the drawing in detail, the reference character 5 indicates the supporting post of the device which is preferably hollow.

This post is sunk in the ground surface in 45 such a way that it will be held in an upright position at all times to support the weight of the persons using the device.

- The reference character 6 indicates a tubular supporting member formed with an 50 opening adjacent to its lower end to accommodate the bolt 7 which bolt is adapted to pass through registering openings 8 in the post 5, which latter openings are arranged in vertical spaced relation with each other 55 so that the supporting post 6 may be adjusted vertically with respect to the post 5.

Threads are formed exteriorly of the supporting section 6 and are arranged adjacent to the upper end thereof, which threads are adapted to be positioned in the threaded 60 opening of the coupling 9 there being provided a supporting washer 10 disposed on the upper end of the tubular supporting section 6 that acts as a support for the bearings 11 between which the balls 12 are positioned.

Associated with the coupling 9 is a head 13 which is provided with an extension 14 threaded as at 15 to accommodate the nuts 16 for securing the head within the coupling 70 9. Bearing members 17 and 18 are arranged between the head 13 and coupling 9 and accommodate the balls 19 that support the weight of the head and persons holding onto the arms 20.

75 These arms 20 are formed with threaded extremities 21 that are positioned in threaded openings formed in the head 13, the arms being of constructions to extend upwardly and outwardly as illustrated by Figure 1 of the drawing.

Bracing arms 22 have connection with the arms 20 and act to hold the arms in their operative positions against sagging under the weight of the persons hanging on the 85 arms.

From the foregoing it will be obvious that due to this construction, the head which supports the arms 20 may be rotated with the minimum amount of exertion on the 90 part of the person using the device.

In the use of the device, persons grab the arms 20 in a manner as illustrated in Figure 1, and a person pushes or pulls on one 95 of the arms to rotate the head to cause the head to rotate at the upper end of the post.

I claim:—

1. In a device of the character described, a hollow supporting member having threads formed at its upper end, a coupling having 100 threads cooperating with the threads of the supporting member to removably secure the coupling in position, a head having a reduced portion extending through the coupling, bearings supported between the head and coupling, a nut on one end of the reduced portion to secure the head on the coupling, said reduced portion extending into the hollow supporting member, and arms extending from the head.

110 2. In a device of the character described, a support, a coupling removably mounted on

the support, a head having a reduced portion extended into the coupling, bearing members disposed between the coupling and head to revolvably support the head, said head having threaded openings, upwardly and outwardly curved arms having threaded extremities fitted in the threaded openings of the head, arms connecting the first mentioned arms and disposed adjacent to the upper surfaces of the first mentioned arms. ¹⁰ In testimony that I claim the foregoing as my own, I have hereto affixed my signature.

WALTER CECIL MILLS.
